UNITED STATES PATENT OFFICE.

MARTIN FREDENHAGEN, OF LA GRANGE, ILLINOIS.

REFRIGERATOR.

Application filed September 22, 1923. Serial No. 664,329.

My invention relates to refrigerators and means of refrigeration, being directed more particularly to a portable type of refrigerator adapted for keeping foods, and particularly 5 ice cream.

One of the features of my invention is a so-called dry freezing or refrigeration, that is, in which no exposed ice or salt is used, the refrigerant being kept in a sealed container 10 adapted to be placed in a suitable insulated container.

Heretofore in handling and delivering ice cream, where it is necessary to pack it so as to keep it cold for a period of time longer than 15 the ordinary melting period, it has been the practice to pack the cream in a pail or can surrounded by chopped ice, which is salted. This is not a very clean or sanitary method of handling the cream, because the ice melts 20 and sometimes the salt water gets into the cream or runs out of the container.

In my improved refrigerator and method of refrigeration, this is done away with as the refrigerant is kept in a sealed container and 25 thus the entire method is clean and dry.

In the accompanying drawings, I have shown the preferred form of refrigerator—

Fig. 1 being a perspective view of the refrigerator, showing the cover removed;

Fig. 2 is a sectional view through Fig. 1 along the line 2—2;

Fig. 3 shows the outer tubular section with the end flaps unfolded;

Fig. 4 shows the inner tubular section of 35 the refrigerator with the end flaps unfolded; and

Fig. 5 shows a form adapted to be used for assembling the tubular sections 3 and 4.

Referring now more in detail to the refrigerator as illustrated, it comprises preferably inner and outer tubular sections, preferably made up of a suitable fiber board, Fig. 3 showing the outer section 10 having downwardly extending portions 11—12 from each 45 of the four walls and adapted to be folded inwardly and overlapped so as to provide a suitable bottom, said overlapping sections being suitably secured, preferably by a waterproof cement, and the meeting edges or cracks 50 sealed. The top extending portions 13—14 of the section 10 are adapted to be folded inwardly as indicated.

In Fig. 4 I have shown an inner tubular section 15 of such a size that it may be inserted 55 in the outer section 10 and provide intervening spaces between the walls for insulating

purposes. The lower ends 16—17 of said inner section are adapted to be folded inwardly and overlapped. They are then suitably secured and sealed, preferably by a water-proof 60 cement. The upper ends 18—19 are adapted to be folded outwardly as shown, so that they may overlap with the upper ends 13—14 of the outer section.

To assemble the tubular sections I provide 65 a hollow block 20 constructed so that the inner section 15 may be inserted inside the block and the outer section 10 placed over the block. Before turning the ends of the section over I place strips of wood as 21—22 around the four 70 sides, then fold or turn the upper extensions 13—14 and 18—19 so that they overlap. I then drive nails 23 through the overlapping portions into the wood sections 21—22, thereby firmly holding the parts together. I then 75 draw the wood block 20 out of the assembled sections.

The bottom flaps 16—17 of the inner section 15 may be turned and sealed, as already indicated, either before or after assembling 80 with the section 10. But after the block 20 is drawn out of the assembled sections, and before the bottom flaps 11—12 of the outer section 10 are sealed, I insert a suitable insulating material 23 in the intervening space 85 between the walls of the sections, preferably using hair felt as it is comparatively cheap, and serviceable. I also fill the bottom space 24 with the same insulating material, and then fold over the bottom flaps 11—12 and 90 seal the same. I now cover the bottom by applying a fabric 25, doing the same over the bottom flaps.

The outer or food container is now completely assembled, with a central opening of 95 a suitable size.

Where it is to be used for ice cream, I preferably make the opening of a size to take one or more bricks, leaving sufficient space therein to insert a container with refrigerant, as 100 will be more fully described.

In order to close the container I provide a suitable top made up of a wood cover 26 having an insulated face 27 and a hair felt block 28 of a size to fit snugly into the central opening of the container so as to be held thereon.

Now as to the refrigerant, I preferably provide a container adapted to hold a solution which may be frozen therein so that the 110 entire element consists of a cold, dry refrigerant. To this end I provide a metal can 29,

arranged to receive the refrigerant element, this being preferably a brine solution adapted to be frozen in the can to about zero and which will not melt under about 18 degrees 5 Fahrenheit. A solution having a specific gravity of approximately 50 on the salinometer works well and comes within the aforesaid temperatures, thereby providing a frozen solution which will begin to melt at 10 about 18 degrees Fahrenheit, which is the temperature at which good ice cream will freeze. This I find very suitable for use in connection with ice cream where it is to be packed and delivered in a local territory. 15 Thus in the use of the refrigerator and carrying out my method of refrigeration, I place the article to be delivered, such as a brick of ice cream 30 therein. I then insert the frozen refrigerant 29 into the container 20 and place the cover 26 thereon.

It is now ready for delivery and may be very readily handled, being clean and dry and maintaining the ice cream below melting point for a period of time sufficient to cover 25 ordinary conditions of delivery and use.

What I claim as new and desire to secure by United States Letters Patent is:

1. A refrigerator casing comprising two tubular sheet material sections, one inserted 30 in the other, the inner section having end portions turned inwardly and overlapping to form a sealed bottom, the outer section hav-

ing end portions turned inwardly and overlapping to form a sealed bottom, said sections having intervening insulated spaces between the walls, and means for securing the sections at the top to seal the same. 35

2. A refrigerator casing comprising two tubular sheet material sections, one inserted in the other, the inner section having end 40 portions turned inwardly and overlapping to form a sealed bottom, the outer section having end portions turned inwardly and overlapping to form a sealed bottom, said sections having turned over overlapping ends 45 secured together to seal the top across the intervening space between the walls.

3. A refrigerator casing comprising two tubular sheet material sections, one inserted in the other, the inner section having end 50 portions turned inwardly and overlapping to form a sealed bottom, the outer section having end portions turned inwardly and overlapping to form a sealed bottom, said inner section having end portions turned outwardly and said outer section having end 55 portions turned inwardly with said inner and outer portions overlapping and secured to seal the top across the intervening space between the walls. 60

In witness whereof, I hereunto subscribe my name this 20th day of August, A. D., 1923.

MARTIN FREDENHAGEN.
